UNITED STATES PATENT OFFICE.

STEPHEN W. WEST, OF NEW YORK, N. Y.

DESIGN FOR A SHOE.

SPECIFICATION forming part of Design No. 23,366, dated June 12, 1894.

Application filed March 10, 1894. Serial No. 503,208. Term of patent 8½ years.

To all whom it may concern:

Be it known that I, STEPHEN W. WEST, a citizen of the United States, residing in the city of New York, county and State of New York, have invented and produced a new and original Design for a Shoe, of which the following is a specification, reference being had to the accompanying drawing, forming part thereof, in which the figure is a perspective 10 view of a shoe, showing my design.

The leading feature of the design is the side opening having the angular boundary lines as shown.

The shoe is of the usual shape and may be

of any desired style but the opening is at the 15 side and is bounded by the vertical or perpendicular line 10 merging at its lower end into the forwardly and downwardly extending line 11 which terminates at the edge of the upper. 20

I claim—

The design for a shoe, herein shown and claimed.

STEPHEN W. WEST.
